ATOMIZER

Edward B. Hunn, Cranford, N. J., assignor to
Stanco Incorporated, a corporation of Delaware

Application January 10, 1942, Serial No. 426,305

1 Claim. (Cl. 128—175)

This invention relates to a small compact atomizing device of size and shape convenient for carrying about one's person and suited for dispensing liquids in a dense finely diffused spray from liquid impregnated materials contained therein. The invention relates particularly to a small pocket size relatively inexpensive atomizer device for injecting medicinal liquids into the nasal and oral passages of the body in a relatively uniform finely diffused spray from liquid impregnated materials charged to and sealed into the device at the time of its manufacture.

The invention may be fully understood from reading the following description and the illustrations afforded in the accompanying drawing of specific embodiments, the same numerals being given to similarly related parts.

Figure I is a vertical view of one form of the assembled atomizing device, partly in section, showing the five principal parts of the atomizer, 20 namely:

- (a) Cap member (1).
- (b) Body member (10).
- (c) Compression member or pressure element (20).
- (d) Absorbent packing (30).
- (e) Sealing member (40).

Figure II is a cross sectional view along the line I—I of Figure I.

Figure III is a vertical sectional view through the unassembled atomizer device with the parts relatively arranged as to indicate the manner of assembly;

Figures IVa, IVb, and IVc are vertical sections through various end forms of the nozzle portion of the body member 10, showing particularly variations in thickness of materials through which the atomizer hole of the same chamber is pierced;

Figure V is a vertical view of a second form of the assembled atomizing device, partly in section, showing the same five parts; Va showing the absorbent packing member suitable therefor, separately; and

Figure VI is a vertical view of a third form of the assembled atomizing device, partly in section, showing the same five parts; VIa showing the absorbent packing member suitable therefor, separately.

The cap member 1 is simply a dust cap made of any suitable rigid material, not acted upon or corroded by the materials used in the atomizer. Materials such as glass, molded plastics and metals are generally considered suitable. The

cap is made to fit over the nozzle 11 of the body member 10 either by a friction fit, or preferably by means of screw threads 2 (or slots) adjusted to move upon the screw threads 12 (or lugs) on the nozzle 11 of the body member 10. The cap is usually between $\frac{1}{2}$ " and $\frac{3}{4}$ " long and of conical or hemispherical external shape. The cap may, or may not, be fitted with a gasket 3.

The body member 10 is a tubular element open at one end and closed near the opening above the nozzle by the septum 13. The tubular element may be externally either of circular or polygonal cross section and internally preferably of either circular or rectangular cross section. It may be made of any suitable rigid material not acted upon or corroded upon by liquids used in the atomizer such as glass, metal, etc. but preferably is of either molded plastic or metal. The tubular element is usually between $1\frac{1}{2}$ " and $1\frac{3}{4}$ " long and of minimum wall thickness consistent with rigidity of construction as determined by the nature of the material of fabrication. Thus, when plastic materials are employed the thickness will be greater than when metallic materials are employed. In the center of the septum 13 a hole 14 is made of diameter of about $\frac{1}{60}$ ", which serves as the orifice through which the liquid is atomized. It is important to stress that while the main portion of the septum 13 may be of any thickness, as shown in Figures IVa, b, and c, it is essential that the thickness at the hole 14 be about 0.025 inch or less in order that the atomizing device function satisfactorily. The open end of the tubular member is so constructed as to receive the compression member or bulb 20 in air-tight, fluid-tight connection. The manner in which the connection between the body member 10 and the compression member 20 is made is optional as indicated in Figures III, IV and V. In Figure III there is shown about $\frac{3}{16}$ " from the open end of the body member 10 an annular enlargement 15 against which is pressed in friction fit over the free end of the body member the portion of the compression member 20 which has an inwardly directed flange 21 and a terminal annular enlargement 22 so that the sealing member 40 may be pushed over the junction and if necessary over the annular enlargement 15 of the body member 10 and the compression bulb 20 in air-tight and fluid-tight connection. An alternative manner of providing an air-tight, fluid-tight fit of the compression member 20 over the body member 10 is, as shown in Figure V, to have the compression member 20 provided with a terminal

inwardly directed flange 23 which can fit into a grooved portion 16 on the body member and is sealed in air-tight, fluid-tight connection by the band or ring seal 40.

In Figures I, III and V the body member is adapted to receive the uniformly shaped prism of absorbent packing. In Figure VI the body member is of shape adapted to receive an absorbent packing member 30 which has a forwardly projecting portion of small cross section 30a.

The compression member or pressure element 20 consists of a cylindrical piece of rubber or other resilient material open at one end. When the liquid to be atomized is an oil, it is preferable to have this compression member made of neoprene or other synthetic rubber which is not affected by contact with oils. Sometimes in the compression member there is an air hole 24 of about $\frac{1}{16}$ " in diameter in the side of the bulb over which the thumb, in the use of the atomizing device, is expected to be placed during the compression stroke.

The absorbent packing member 30 consists of any suitable absorbent, porous material such as felt, cotton, chalk, or even wood. The absorbent packing material 30 usually, though not necessarily, completely fills the inside of the body member and in the assembled unit it is fitted into the body member so as to be under slight pressure against the septum 13 and the nozzle opening 14. This absorbent material is saturated with the liquid to be atomized. It is usual to have this packing material made of one piece which completely fills the body member 10 with a slight amount of compression against the opening 14. In some cases, it is advantageous to have the absorbent material merely as a core in the body member. The most practical shape for the packing member 30 is in the form of a rectangular prism prepared from sheets of absorbent material. In Figure III the packing is of rectangular, prism shape; in Figure V, of rectangular shape, and in Figure VI, of rectangular prism shape with a forwardly projecting portion of smaller cross section than the main portion.

The sealing member 40 consists of a band or ferrule made of metal or other suitable material which is crimped or cemented over the joint between the body member 10 and the compression member 20. The preferred form of this sealing member is a thin metal ferrule or band which is slipped over the compression member or pressure element after assembling and then the open end of the ferrule is crimped, or rolled, over the annular enlargement 15 of the body member. However, any other suitable means of holding the compression member to the body member may be employed, as for example, a cellulose band, which after application and drying, shrinks.

In the assembled atomizer device, as illustrated in Figure I, the body member 10 is usually closely packed with absorbent material of the nature of felt and impregnated with medicinal liquid, so as to be under slight pressure against the septum 13 and the opening 14 therein. The packing material 30 may consist of one portion, or a series of discs suitably impregnated with the liquid. When the compression member 20 is compressed, air is forced through the packing material, which, emerging from the small hole 14, develops a finely diffused dense spray of the liquid. When the hole 24 is pierced or is made in the compression member, the release of the bulb to its nor-

mal form occurs without drawing in air through the hole 14. By proper selection of the nature of the absorbent packing 30 various degrees of density of liquid in the spray may be obtained.

5 The less dense materials, such as loosely compacted felt providing for a high liquid content in a spray, while such materials as fine pumice and chalk reduce liquid content.

When the absorbent material 30 completely fills the body member it is particularly advantageous in the functioning of the atomizer to have the hole 24 in the compression member. When the absorbent material 30 is completely saturated, no liquid is drawn into the bulb on the 10 release stroke if the hole is uncovered, thus preventing any deposition of the valuable medicament in the bulb or air through the opening 14.

The assembled device functions as a small, highly effective atomizer by forcing air from the 20 compression member 20 through liquid saturated material when the absorbent material 30 completely fills the body member 10 or over the exposed surface of the liquid saturated material when the absorbent material is merely a core in the body member 10 and thence through the small hole 14 near the end of the nozzle 11 of the body member. Sometimes the compression member is connected to a tube extending some distance into the packing, but this is not usual.

25 The presence of the hole 24 in the compression member 20 is advantageous in the functioning of the atomizer device on the release stroke, thus eliminating one of the main causes of clogging of the opening due to mucous being drawn in and extremely difficult to remove, because of the smallness of the hole and the nature of mucous material. Furthermore, without the hole 24 it is impossible to utilize a large portion of the liquid contained in the absorbent packing. Apparently this is because the liquid is pushed back from the nozzle opening by air upon the release stroke. With the hole 24 all the air which goes through the packing is outward and tends to force the liquid towards the nozzle. This makes for more complete utilization of the medicament contained in the absorbent packing 30. The construction of the nozzle 11 so that the hole 14 is some distance from the end is highly advantageous when the device is employed as an atomizer for the nasal passages in preventing mucous from being drawn into the atomizer when the pressure on the bulb is released.

Embodiments

55 1. The general nature of this embodiment is given in Figure I. The cap member 1 and the body member 10 are made of molded plastic material of about 0.025 inch thickness. The cap member is of conical shape of $1\frac{1}{16}$ " size. The cap is inwardly threaded to engage upon the threaded nozzle portion of the body member 10 of $1\frac{1}{16}$ " long onto which there is fitted an elongated bulb 20 with a hole 24 as an air vent. The connection between the bulb 20 and the body member 10 is sealed by the ferrule of thin metal 60 40. The packing material is of a rectangular prism shape having sizes of $\frac{3}{8}$ " and $1\frac{1}{2}$ " long. The hole 14 is approximately $\frac{1}{60}$ " in diameter. When suitably impregnated with medicinal liquid, the device provides a simple and effective means of forming a finely dense spray of the medicinal liquid.

70 2. This form of an atomizing device is shown in Figure V. The cap and body members are

formed of molded plastic material of about 0.025 inch thickness. The body member is externally of circular cross-section of $\frac{5}{8}$ " in diameter and internally of square cross-section of side $\frac{3}{8}$ ". The body member is $1\frac{1}{4}$ " long with internal space for holding the absorbent impregnated felt material 30 of $1\frac{1}{2}$ " long. The hole 14 in the septum 13 is $\frac{1}{80}$ " in diameter. The compression bulb 20 has an air vent 24 therein. The connection between the compression member 20 and the body member 10 is made by the fitting of the inwardly directed flange 23 of the compression member in the groove 16 on the body member. The seal is made by the crimping of the member 40 over the forwardly projecting edge of the annular enlargement of the body member 13.

3. Embodiment 3 differs from Embodiment 2 only in having an absorbent packing material 30 of smaller forwardly projecting cross-section than the main body of the absorbent material, and in having a gasket 13 in the cap member.

Although the invention has been disclosed with reference to specific embodiments thereof,

it is not intended that any limitation shall be implied thereby, the novelty and scope of the invention is duly set forth in the following claim.

5. What is claimed is:

An atomizer device for injecting medicinal liquids into the nasal and oral passages of the body, which comprises a tubular body member open at its inlet end and provided with a nozzle 10 at its discharge end adapted for insertion into said passages, a septum across the body member at the base of the nozzle and provided with a small atomizing hole of about $\frac{1}{80}$ inch in diameter, a compression bulb 20 engaging the inlet end of the tubular body member in airtight, fluid-tight relation, the bulb having an air hole to permit direct inflation with air, a body of absorbent material containing the medicinal liquid disposed within the body member compressed between the septum and the bulb and substantially covering the hole in the septum, and a cap removably affixed to the nozzle carrying a gasket adapted to provide a fluid seal against the discharge end of the nozzle.
